UNITED STATES PATENT OFFICE.

GEORGE C. BREIDERT, OF CHICAGO, ILLINOIS, ASSIGNOR TO AUTO UTILITIES MANUFACTURING COMPANY, OF CHICAGO, ILLINOIS, A CORPORATION OF ILLINOIS.

VENTILATOR.

1,097,387.

Specification of Letters Patent. Patented May 19, 1914.

Application filed November 11, 1912. Serial No. 730,684.

To all whom it may concern:

Be it known that I, GEORGE C. BREIDERT, a citizen of the United States, residing at Chicago, in the county of Cook and State of Illinois, have invented certain new and useful Improvements in Ventilators, of which the following is a specification.

My invention relates to ventilators of the sort adapted to be placed on the outside of a car, building, or the like, and so constructed that drafts of air, naturally or artificially produced, bring about the exhaustion of the foul air from the space to be ventilated.

One of the principal objects of the invention is to provide a ventilator of this type which will be simple in its construction and cheap to manufacture, which will involve no movable or adjustable parts, and which, while utilizing the movement of the outside air to the fullest extent to cause the exhaustion of the impure air from the space to be ventilated, will not permit wind, rain, snow, dust and the like to blow or be forced or driven into the inclosed space through the openings in the ventilator.

The invention has in view more particularly to provide a suitable ventilator for railway cars which may be placed either vertically over an opening in the roof of the car, or in horizontal position outside of a window or opening in the clear-story, when the car is of that type, and so constructed that it presents an air resisting surface in the direction of the movement of the car which is utilized to produce a suction through the ventilator that exhausts the foul air from the interior of the car.

The invention has for further objects the other new and improved constructions, arrangements and devices relating to ventilators to be hereinafter described and claimed.

The invention is illustrated, in certain typical embodiments, in the accompanying drawings wherein—

Figure 1 is a view, in perspective, of one form of the invention. Fig. 2 is a sectional plan of the same. Fig. 3 is a vertical sectional view taken on the line 3—3 of Fig. 2. Fig. 4 is a sectional plan similar to Fig. 2 showing a slight modification.

Like characters of reference designate

like parts in the several figures of the drawings.

55

Referring first to Figs. 1 to 3 inclusive, the device may be said to consist of a box-like structure mounted upon or provided with an annular base or neck 10. The box-like structure is formed of an inner or lower plate 11 formed with a central opening 12, an outer or upper end 13, preferably imperforate, forward and rear faces 14, and side walls 15, the side walls falling short of the forward and rear faces 14 so as to provide outlets 16 at the corners of the structure. Within the structure are deflecting walls 17 preferably angular in cross section as best shown in Fig. 2, and provided centrally with openings 18 by means of which the inlet, through the base 10, communicates with the outlet passages 19 formed between the deflecting walls 17 and the forward and rear faces 14. The faces 14 are preferably formed with the central bulging or V-shaped portions 20.

60

The device above described is used and operated in the following manner: It is placed either in the vertical position shown in the figures over an opening in the roof of the car, or else horizontally, that is, with one side wall 15 uppermost and the base or neck communicating with an opening or window of the clear-story of the car. In either position one of the faces 14 will ram the air as the car moves. This results in drafts of air of considerable velocity passing over the outlet openings 16 which produces a suction through the openings 18 and 12 which withdraws the foul air from the space to be ventilated. The faces 14 are 65

70

preferably arranged so that the air impinges thereon at right angles and has to make a right angle turn around their outer edges and over the openings 16. In the 75 construction shown, the center portions 20 of the faces 14 are bulged out into V-shape, primarily for the purpose of widening the exhaust passages 19 opposite the openings 18 so as to prevent choking and back draft 80 and also so as to deflect impinging air toward the exhaust openings 16. The portions of the faces on opposite sides of the V-shaped portions are preferably flat and 85

90

preferably stand at substantially right angles to the planes of the outlets 16. The in- 95

90

100

105

ner walls 17 are given the angular configuration so as to prevent the wind from blowing into the car through the openings 16 and 18. The V-shape of the faces 14 5 allows the air impinging against the portions of the wall 17 adjacent the openings 18 to sweep around said openings without choking the exhaust therethrough. The side walls 15 are preferably concaved in 10 order to give the air an outward sweep past the rear openings 16 although this is not essential. Obviously the device need not be provided with the base or neck 10. The configuration and proportions of the device 15 may, of course, be changed as the circumstances of any particular installation require.

Fig. 4 shows a slight modification intended to be used particularly when the ventilator is placed in what has been termed the horizontal position. In this construction the deflecting walls 17^a are formed above the openings 18 with projections or eaves 17^b, the purpose of which is to deflect water, 20 dirt, or other matter, and prevent the same from entering the car through the openings 18.

While I have described my invention in certain preferred embodiments, it will be 25 readily understood that further modifications may be devised without departure from the principles of the invention.

I claim:

1. A ventilator of the character described, 30 comprising a box having an inlet, imperforate faces having central bulging sections and lateral flat sections extending therefrom, imperforate sides forming between them and said flat sections interposed outlet openings, and interior deflecting walls 35 extending between said imperforate faces and connecting the opposite sides at their corresponding lateral edges to form with said sides a chamber within the box open 40 to said inlet, said walls being formed of members of angular cross-section forming openings between them by which said outlet openings communicate through said chamber with said inlet.

2. A ventilator of the character described, 45 comprising a box having an inlet, imperforate faces having central V-shaped sections and lateral flat sections extending therefrom, imperforate sides forming between them and said flat sections interposed outlet openings, and interior deflecting walls joining corresponding edges of 50 said sides to form therewith a chamber within the box open to said inlet, said walls being formed of members of general V-shape, in cross-section forming openings between them by which said outlet openings communicate with said inlet, and the apexes 55 of said members extending inwardly.

3. A ventilator of the character described,

comprising a box provided with an open base, a closed outer end, relatively opposite imperforate air-ramming and deflecting faces having central bulging sections and lateral flat sections extending therefrom, 70 and relatively-opposite imperforate side walls forming openings between their edges and those of said faces, and interior deflecting walls extending between said faces and joining corresponding edges of said side walls to form therewith a chamber within the box open to said inlet, said deflecting walls being formed of members of general V-shape in cross-section forming between them openings through which said outlet openings communicate through said chamber with said inlet. 75 80

4. A ventilator of the character described, 85 comprising a box provided with an open base, a closed outer end, relatively opposite imperforate air-ramming and deflecting faces having central bulging sections and lateral flat sections extending therefrom, and relatively opposite imperforate side walls presenting concave outer surfaces and forming openings between their edges and those of said faces, and interior deflecting walls extending between said faces and joining corresponding edges of said side walls to form therewith a chamber within 90 the box open to said inlet, said deflecting walls being formed of members of angular cross-section forming between them openings through which said outlet openings communicate through said chamber with 95 100 said inlet.

5. A ventilator for cars or the like, comprising a box-like structure formed with an opening communicating with the interior of the car, and with exhaust openings at opposite sides, and provided with oppositely disposed air-ramming faces arranged transversely to the direction of travel of the car and terminating at said exhaust openings, the edges of said air ramming faces along 105 110 said exhaust openings extending out as far in each case as any part of the structure capable of obstructing air on that side of the ventilator.

6. A ventilator for cars and the like, comprising a box-like structure closed except for an opening communicating with the interior of the car and relatively opposite exhaust openings, and provided with air ramming faces having flat surfaces terminating 115 at said exhaust openings and disposed at right-angles to the direction of travel of the car.

7. A ventilator for cars and the like, comprising a box-like structure formed with an opening communicating with the interior of the car and with exhaust openings at opposite sides, and provided with air ramming faces having surfaces terminating at said 120 125 exhaust openings, disposed at right angles 130

- to the direction of travel of the car, the edges of which adjacent said exhaust openings extend out as far in each case as any part of the structure capable of obstructing air on that side of the ventilator.
8. A ventilator for cars and the like comprising a box-like structure formed with an opening communicating with the interior of the car and provided with oppositely arranged air ramming faces disposed transversely to the direction of travel of the car, and with side members which do not project outwardly beyond the outer edges of said air ramming faces and are spaced away from said air ramming faces so as to provide exhaust openings at the corners of said structure.
9. A ventilator for cars and the like comprising a box-like structure formed with an opening communicating with the interior of the car and provided with oppositely arranged air ramming faces disposed transversely to the direction of travel of the car, and with side members which do not project outwardly beyond the outer edges of said air ramming faces and are spaced away from said air ramming faces so as to provide exhaust openings at the corners of said structure, the portions of said air ramming faces adjacent said exhaust openings standing in each case at an angle to the plane of the contiguous opening which is not greater than a right-angle.
10. A ventilator for cars and the like comprising a box-like structure formed with an opening communicating with the interior of the car and provided with oppositely arranged air ramming faces disposed transversely to the direction of travel of the car, and with side members which do not project outwardly beyond the outer edges of said air ramming faces and are spaced away from said air ramming faces so as to provide exhaust openings at the corners of said structure, said side members being formed with inwardly extending wall sections providing passageways through said ventilator from side to side which communicate with said first-named opening.
- 50 11. A ventilator for cars and the like comprising a box-like structure formed with an opening communicating with the interior of the car and provided with oppositely arranged air ramming faces disposed transversely to the direction of travel of the car, and with side members which do not project outwardly beyond the outer edges of said air ramming faces and are spaced away from said air ramming faces so as to provide exhaust openings at the corners of 60 said structure, said air ramming faces being formed with central V-shaped projections and said side members with inwardly extending angular wall sections arranged to provide central openings.
- 65 12. A ventilator for cars and the like comprising an air ramming face formed with a central V-shaped projection and with surfaces at the sides of said projection which stand substantially at right-angles to the direction of travel of the car, and a wall arranged back of said air ramming face, the extremities of which do not project out beyond the corresponding edges of said face, said wall being formed with a central opening 70 communicating with the interior of the car and with angular bends projecting away from said face at each side of said opening.
- 75 13. A ventilator for cars or the like comprising a box-like structure formed with an opening communicating with the interior of the car, and with exhaust openings at opposite sides, and provided with oppositely disposed air ramming faces arranged transversely to the direction of travel of the car, 80 formed with centrally disposed bulged deflecting portions and terminating at said exhaust openings, the edges of said air ramming faces along said exhaust openings extending out as far in each case as any part 85 of the structure capable of obstructing air on that side of the ventilator.
- 90 14. A ventilator for cars or the like comprising a box-like structure having an inner end wall formed with an opening communicating with the interior of the car, an imperforate outer end wall, a pair of oppositely disposed air ramming faces arranged transversely to the direction of travel of the car and between said inner and outer end 95 walls, and side members between said air ramming faces providing exhaust openings; the edges of said air ramming faces adjacent the sides having the exhaust openings of the structure extending out as far in each case 100 on that side of the structure as any part thereof capable of obstructing air.
